UNITED STATES PATENT OFFICE.

SIDNEY W. PHELPS, OF SOUTHERIDGE, MASSACHUSETTS.

TIME-TABLE.

1,112,089.

Specification of Letters Patent. Patented Sept. 29, 1914.

Application filed September 8, 1910. Serial No. 530,347.

To all whom it may concern:

Be it known that I, SIDNEY WARREN PHELPS, a citizen of the United States, and a resident of Southbridge, in the county of 5 Worcester and State of Massachusetts, have invented certain new and useful Improvements in Time-Tables, of which the following is a specification, reference being had to the accompanying drawings.

10 My invention relates to improvements in time-tables and has for its leading object the provision of an improved device which may be readily placed in a station or other public place and which will serve to satisfactorily 15 denote the departure of various trains on electric or steam roads, the departure of the mails and other information of a like pur- port.

The further object of my invention is the 20 provision of a device of this character which shall be so constructed as to automatically warn a person looking at the same when the time for the departure of his train is approaching and which will obviate the neces- 25 sity for frequently examining a complicated time-table to determine the exact time of departure of a train and then examining a clock to see how long the time is before the train should depart, as is now necessary.

30 Other objects and advantages of my im- proved time-table will be readily apparent by reference to the following description taken in connection with the accompanying drawings, and it will be understood that I 35 may make any modifications in the specific structure shown and described within the scope of my claims without departing from or exceeding the spirit of my invention.

Figure 1 represents a front view of one 40 form of my invention. Fig. 2 represents a vertical sectional view thereof. Fig. 3 represents a front elevation of a slightly modified form of my invention adapted for use in denoting the departure of a larger 45 number of trains leaving at irregular intervals, and Fig. 4 represents an enlarged detail view of one of the minor dials.

In the drawings, numeral 1 designates an 50 ordinary clock which is supported by the frame 2 having the large dial 3 with the smaller clock dial 4 arranged concentric therewith.

Traveling over the face of the clock dial 4 is the ordinary hour hand 5, while also 55 traveling over the face of the clock dial is

the minute hand 6 having an extension 7 traveling over the main dial 3. The said main dial 3 is divided into a plurality of circular spaces bearing therein the numbered circles 8, the numerals within the minor 60 circles 8 referring to certain configurations disposed at the corners of the dial 3 exterior to the outermost circle inscribed upon the dial. These outer designations, as will be readily observed by reference to the drawings, denote trains departing at different hours, for example—the numeral 9 located at the left hand of Fig. 1 in alinement with the numeral IX on the clock dial indicates a train departing at 6:45 from Southbridge 65 for Webster and Boston. It is merely necessary to look in the corners of the dial and find the train one desires to take and then locate the corresponding number therefor on the dial. Then as the hour hand passes 6 the minute hand will be approaching the numeral 9 on the dial 3 as well as the numeral IX on the clock dial and consequently 70 as the pointer 7 reaches the numeral 9 it will be the time for the train designated by that numeral to depart and one may readily calculate how long it is before any certain train leaves.

It will be understood that the form of in- 75 vention just described may be best employed when trains leave at a certain time each hour or when but few trains are leaving during the day. To denote trains leaving at odd times during the day, or to cause the dial to denote both the hour and the minute at 80 which a train departs, I may place at the circles 8 the small dials shown on the clock in Fig. 3 and in detail in Fig. 4 having rotatably mounted thereon the hand 9. In this 85 form of the invention the hand 9 is set by the person having charge of the time-table to point to the hour at which the train leaves, while the dial itself is disposed on an imag- 90 inary line extending radially from that designation upon the clock dial indicating the minute at which the train is scheduled to depart. Taking as an example the upper left hand dial in Fig. 3 having its pointer 95 directed toward the numeral 3 on the dial, the train whose time of departure is to be 100 designated by this dial will leave at five minutes of 3.

If desired, however, to insure an exact un- 105 derstanding of the time of departure of trains two hands may be provided on each 110

- of the smaller or supplemental dials, as indicated for example in Fig. 4. In this event one hand may be set for the hour, the other for the period of time before or after that 5 particular hour at which the train leaves, departure of a train at quarter of twelve being indicated by the dial in Fig. 4, it being understood that this dial would be located substantially in line with the radius on which 10 the numeral 9 of the clock was disposed, so that both the position of the dial and one of the hands on the dial would serve to denote that the train referred to by this dial, left at a quarter before the hour.
- 15 The dial may either contain therein suitable configurations for denoting the designation of the train, or merely a numeral referring to the writing on the spaces 11^a, as may prove least confusing and most 20 visible from the number and size of the small dials on the face of the clock.

The clock in Fig. 3 instead of being shown with continuous circles dividing its dial has been illustrated as divided by quadrants or 25 less of concentric arcs of different radii, the number of arcs being dependent upon the number of minor dials which it is desired to place on any given imaginary line, and the size of the dials being controlled by the 30 size of the space for receiving the same.

From the foregoing description taken in connection with the accompanying drawings, the construction and operation of my improved time-table should be readily understood, and it will be seen that I have provided an efficient device of this character which may be readily installed and which while requiring but slight attention will prove extremely desirable and efficient in either 35 supplementing or taking the place of the ordinary complicated time-table and in serving to convey an automatic warning to a person looking at the same that his train is about to depart and thus preventing the 40 missing of trains, which often occurs when 45

people forget the exact time their train departs, or do not read the time-table correctly although in the station waiting for the train.

I claim:

1. A time-table including a clock having 50 one of its hands formed with an extension, a dial over which the extension passes, minor dials arranged on said main dial and corresponding in position with certain of the minute designations of the clock, means carried by the said minor dial and serving in conjunction with the extension of the clock hand to designate the exact time when a certain event indicated by the dial is scheduled to occur. 60

2. A time-table including a dial, a clock having an ordinary hour hand traveling over the central portion of the dial and a minute hand having an extension traveling over the major portion of the dial, supplemental dials 65 arranged on the main dial and corresponding in position to certain of the minute designations of the clock, hands carried by the supplemental dials for indicating a certain hour, and configurations disposed on the 70 face of the minor dial and referring to a second set of configurations, said second set being disposed at one corner of the main dial, whereby the two sets of configurations serve to denote a certain scheduled occurrence and the hour designating hand on the supplemental dial serves to indicate the hour near which the event is to occur and the position of the supplemental dial indicates the 75 minutes before or after the hour for the occurrence of the event, the approach of the minute hand of the clock to the supplemental dial denoting the approach of said time. 80

In testimony whereof, I affix my signature, in presence of two witnesses.

SIDNEY W. PHELPS.
